UNITED STATES PATENT OFFICE.

HENRY F. BAKER, OF GAINESVILLE, GEORGIA.

OIL-BURNER.

1,097,071.

Specification of Letters Patent. Patented May 19, 1914.

Application filed August 21, 1913. Serial No. 786,016.

To all whom it may concern:

Be it known that I, HENRY F. BAKER, a citizen of the United States, residing at Gainesville, in the county of Hall and State 5 of Georgia, have invented a new and useful Oil-Burner, of which the following is a specification.

This invention relates to improvements in oil burners and more particularly to that 10 class of oil burners which may be installed within cooking ranges and positioned directly upon the grate thereof.

An object of the present invention is to provide an improved form of oil burner 15 wherein the burner tube extends centrally of an air directing conduit, the air being admitted through an annular opening in the base which is adjacent the inner periphery of the said air directing conduit, and the 20 portion of the base directly beneath the said burner tube forming a pan for the receiving of sufficient liquid fuel for the initial heating of the vaporizing tubes.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a side view in elevation of my improved oil burner. Fig. 2 is a vertical 40 cross sectional view taken through the longitudinal axis thereof. Fig. 3 is a top plan view of my improved burner showing one of the air directing conduits in cross section. Fig. 4 is a vertical cross sectional view taken through one of the air directing conduits.

Referring to the drawings in which similar reference numerals designate corresponding parts throughout the several views, 1 is 50 a supporting base and is provided with an upstanding flange 2 extending completely therearound and formed integral with the end posts 3. The end posts 3 act as standards for vaporizing tubes which extend parallel to the base 1 and are positioned a distance thereabove. The base 1 is provided

with the two elevated platforms 4—4 adjacent the ends of the same, upon which platforms are positioned the burner tubes and air directing conduits. The elevated platforms 4—4 are of the same thickness as the remaining portions of the base but are spaced a slight distance thereabove, thereby preventing any foreign material from coming directly into contact with the under portions of the platforms through which the air is delivered to the burner tube. Extending through the platforms 4—4 are the annular openings 5, the same being provided with upstanding rims 6 at the inner and outer peripheries thereof. The annular openings 5 are adapted to supply air from beneath the base 1 which when installed in a cooking range will be from the ash pit to and around the burner tubes whereby the gas will be 75 mixed with a suitable quantity of air for the burning thereof. In order that the gas supplying pipes 7 may communicate with the upstanding burner tubes 8, the peripheral rims 6 are cut away and join at 9, and 80 the annular openings 5 are stopped at this point. In order to further strengthen the central portion defined by the inner peripheral rims 6, webs 10 extend across the annular openings 5 and suitably strengthen the 85 pans 11.

The air directing conduits 11' are formed with a lower cylindrical portion 12, the same adapted to rest upon the platforms 4 of the supporting base and to encompass the 90 upstanding outer peripheral rims 6 of the annular openings 5. In order that the said cylindrical portion 12 may rest flush upon the platforms 4, the same is suitably notched as at 13 so as to accommodate the gas supply pipes 7. The upper extremity of the air directing conduit 11' is frusto-conical in outline as at 15, the same being formed integral with the lower cylindrical portion 12. 95

The burner tubes 8 are provided with the 100 caps 16 secured to the top thereof and through which cap extends a slight opening forming a suitable gas duct 17, the same being positioned slightly above the lower extremity of the frusto-conical portion 15 105 of the air directing conduit, attention being called to the concaved manner in which the upper extremities of the caps 16 are formed to thereby render the cleaning of the caps more easy and to further procure an even 110 distribution of the gaseous fuel. The gas supplying pipes 7 are provided with suit-

able couplings and thereby communicate with the vaporizing tubes 18 and 19. The vaporizing tube 19 communicates with a suitable regulating valve 20 which is intended to be positioned externally of the range and communicates with an oil feed pipe 21. The vaporizing tube 19 extends through suitable apertures formed in the end posts 3 and extends above the upper extremity of the burner tubes, communicating with the second vaporizing tube 18 by the return coupling 22. The vaporizing tube 18 extends across the burner tube and communicates with a downwardly extending pipe 23, the latter communicating with the pipe 24 which extends along the supporting base and communicates with the gas supply pipes 7.

Adjustably mounted below and secured to the vaporizing tubes 18 and 19 are the deflectors 25 which comprise the disk members 26 through which extends suitable hold-means, in the present instance a bolt 27, by which the deflector is adjustably secured to the said vaporizing tube and may be positioned directly above the air directing conduit and burner tubes to thereby deflect the flames issuing therefrom to thereby obtain a more efficient heating of the range within which my oil burner is positioned. The portion of the base between the platforms 4 may be filled with a suitable absorbing material (not shown) such as asbestos whereby the same may be saturated with the liquid fuel and suitably burned for the initial heating of the vaporizing tubes and various parts of the burner. The asbestos absorbing material may be omitted and the fuel burnt while in a liquid condition. The pans 11 are also adapted to contain a limited quantity of liquid fuel so that the burner tubes will also be heated during the initial burning of the liquid fuel.

From the foregoing it will be apparent that my improved oil burner may be positioned within an ordinary range and positioned upon the grate whereby the air may only enter from the ash pit to the fire box through the annular openings 5 which extend through the base of the burner.

By constructing the air directing conduit as described, a suitable quantity of air will be admitted therein and will be temporarily stored therein whereby the same will be heated prior to its mixing with the gas which will increase the efficiency of the apparatus. The air entering through the annular openings 5 at the sides of the burner tubes converges toward the same and a uniform mixing of the air and gas will be obtained.

Having thus fully described the invention what I claim to be new and original with me is:

65 1. An oil burner comprising a base with

upstanding posts, said base provided with an opening extending therethrough and with a peripheral rim extending around said opening, an air directing conduit encompassing the peripheral rim and resting upon said base, a burner tube arranged concentrically of said opening and said air directing conduit, a vaporizing tube supported by said posts and extending above said burner tube, said vaporizing tube communicating with the burner tube, and a liquid fuel supply pipe communicating with said vaporizer tube. 70 75

2. An oil burner comprising a base with upstanding posts, said base provided with an annular opening therein and with peripheral rims extending around said opening, an air directing conduit encompassing the outer peripheral rim and resting upon said base, a burner tube arranged concentrically of said annular opening and said air directing conduit, a vaporizing tube supported by said posts and extending above said burner tube, said vaporizing tube communicating with said burner tube, and a liquid fuel supply pipe communicating with said vaporizer tube. 80 85 90

3. In an oil burner the combination of a base provided with an opening extending therethrough, a burner tube arranged concentrically of said opening, an air directing conduit comprising an enlarged cylindrical body portion encompassing said opening, the upper extremity of said cylindrical portion formed as a frusto-conical pipe, the lower extremity of which is slightly below the upper extremity of said burner tube, a vaporizing tube disposed directly above said burner tube communicating therewith and adapted to be heated thereby, a liquid fuel supply pipe communicating with said vaporizing tube and adapted to supply liquid fuel thereto. 95 100 105

4. In an oil burner the combination of a base provided with an elevated platform, said platform provided with an annular opening extending therethrough and with peripheral rims extending around said annular opening, an air directing conduit removably resting upon said platform and encompassing the outer peripheral rim, a burner tube disposed concentrically of said annular opening, a vaporizing tube supported above said air directing conduit and burner tube and communicating with the latter, a liquid fuel supply pipe communicating with said vaporizing tube and adapted to supply liquid fuel thereto. 110 115 120

5. In an oil burner the combination of a supporting base provided with an elevated platform, said platform provided with an annular opening extending therethrough and with peripheral rims extending around said annular opening, an air directing conduit tube encompassing said annular open- 125 130

ing and held against lateral shifting by the outer peripheral rim, a burner tube disposed centrally of said annular opening, a cap positioned at the upper extremity of said 5 burner tube and provided with a gas duct extending therethrough, the portion central of said annular opening and within the inner peripheral rim comprising a liquid fuel receiving pan, a vaporizing tube disposed 10 above said burner tube and communicating therewith, and a liquid fuel supply pipe communicating with said vaporizing tube.

6. In an oil burner the combination of a supporting base provided with elevated 15 platforms, said platforms provided with annular openings extending therethrough and with peripheral rims extending around said annular openings, air directing conduit tubes encompassing said annular openings, 20 burner tubes disposed centrally of said annular openings, the portion of said base central of said annular openings and intermediate the inner peripheral rims comprising liquid fuel receiving pans, said pans communicating 25 with the depressed portion between said raised platforms, the said depressed portion adapted to receive liquid fuel there- 30 in for the initial heating of the burner, vaporizing tubes disposed above said burner tubes and communicating therewith, and a fuel supply pipe communicating with said vaporizing tube.

7. In an oil burner the combination of a

base, platforms elevated above the general level thereof and provided with annular 35 openings extending therethrough, said openings provided with upstanding peripheral rims, air directing conduits provided with enlarged lower portions encompassing said annular openings and adapted to contact with the outer peripheral rims thereof and held against shifting thereby, burner tubes disposed centrally of said air directing conduits, the portions within the inner peripheral rims of the annular openings defining 40 liquid receiving pans, said pans communicating with the lowered portion between the raised platforms said lowered portion and pans adapted to burn liquid fuel for the initial heating of the oil burner, a vaporizing 45 tube extending above the said burner tubes and communicating therewith, means carried by the said base and adapted to maintain the said vaporizing tube in an elevated position, a fuel supply pipe communicating 50 with said vaporizing tube and deflectors adjustably secured to the said vaporizing tube and arranged directly above said air directing conduits.

In testimony that I claim the foregoing as 60 my own, I have hereto affixed my signature in the presence of two witnesses.

HENRY F. BAKER.
